FIG. 0.

FIG. 1.

FIG. 8.

Patented Sept. 25, 1923.

1,468,911

UNITED STATES PATENT OFFICE.

FRANK MADLE, OF BERWYN, ILLINOIS, ASSIGNOR TO CRUVER MANUFACTURING COMPANY, OF CHICAGO, ILLINOIS, A CORPORATION OF ILLINOIS.

SAVINGS BANK.

Application filed May 12, 1922. Serial No. 560,355.

To all whom it may concern:

Be it known that I, FRANK MADLE, a citizen of the United States, and resident of Berwyn, in the county of Cook and State 5 of Illinois, have invented certain new and useful Improvements in a Savings Bank, of which the following is a specification.

My invention relates to improvements in coin receivers, particularly of the kind 10 known as pocket savings banks, and has special reference to improvements in means for locking and unlocking the bank and to improvements in guard means for the coin slot.

One object of my invention is to provide a 15 very simple key operable lock which is of substantial construction; which shall automatically lock the cover on the bank; which shall be capable of being opened or unlocked by the use of a very simple key; and which lock shall be so constructed that it 20 shall be difficult to pick the lock or in other words unlock the device with any implement other than by the key which is provided.

Regarding the coin slot guard, it is my object to provide a guard which can be very 25 cheaply constructed; which shall be effective to admit coins of various thicknesses; and which shall not permit the thinner coins 30 to escape.

My invention will be more readily understood by reference to the accompanying drawings forming part of this specification, and in which:—

Figure 1 is an edge view of a shallow 35 round pocket savings bank made in accordance with my invention;

Figure 2 is a top plan view of the main 40 part or body of the bank as it appears when the cover is removed;

Figure 3 is a bottom or underside plan view of the cover;

Figures 4, 5, and 6 are horizontal-sectional 45 views on the lines 4—4, 5—5 and 6—6 of Figures 1 and 8;

Figure 7 is a fragmentary plan-section on the line 7—7 of Figures 1 and 8;

Figure 8 is an enlarged vertical fragmentary sectional view on the line 8—8 of 50 Figure 2;

Figures 9 and 10 are enlarged vertical fragmentary sectional views on the lines 9—9 and 10—10 of Figure 2; and

Figure 11 is a plan view of the key which 55 I employ.

In said drawings, 1 illustrates a shallow round flat box comprising a body or box portion 2 closed at its lower end by a fixed cover 3 and having a cylindrical wall 4 ending in an inturned, flat, narrow, circumferential flange 5 at its upper edge, and a cover member 6 adapted to close the lower or body portion and arranged to be secured and locked in position on the body member. The flange 5 is provided with a plurality of openings 7 and the cover member is provided with a plurality of L-shaped lugs 8 spaced similarly to the openings 7 adapted to be projected through the openings and upon the rotation of the cover to be engaged 70 beneath the flange 5, thus preventing the direct removal of the cover.

The cylindrical wall 4 of the bank is provided with a suitable coin slot 9 between the bottom and top of the bank for permitting the insertion of the coins and the bank is adapted to be opened by the removal of the cover to permit the removal of the coins from the bank.

To lock the cover to the body of the bank, 80 I arrange projections adapted to enter openings in the cover and prevent the rotation of the cover to free the lugs 8 from the flange 5.

The cover 6 comprises an inner plate or 85 wall 10 out of the body of which the lugs 8 are struck up, and an outer wall or member 11 the two walls of the cover being joined at their edges and formed to provide a circumferential depending flange 12 which fits 90 upon the upper end of the main box member 2 so that the cover can be rotated upon the box to engage the lugs 8 beneath the flange 5 as described. The inner plate 10 of the cover member 6 is provided with pairs of 95

openings 13 arranged circumferentially between the several lugs 8 and I provide a pair of projections 14 which are adapted to project through slots 15 in the flange 5 of the body member to extend above said flange 100 and enter the openings 13 in the cover. These projections 14 are formed on the free ends of spring arms 16 of a locking member 17. This member is formed from a sheet of spring metal, the arms 16 being formed by 105 providing the member 17 with a slot 18 extending from one end toward the other end. The opposite end of the member 17 is provided with a slot 19 adapted to receive a tongue 20 struck up from the flange 5 of the 110

body portion, the tongue being adapted to be projected through the slot and bent over the member 17 to retain the member 17 in position with its projections 14 extending through the slots 15 in the flange 5.

For the purpose of forcing the projections downwardly to permit the rotation of the cover for opening the box, I provide a key 21 having a shank 22 and provided with 10 two flat projections 23 and I provide the wall 4 of the box with a slot or opening 24 through which the operating part of the key can be projected into the bank above the arms 16. The opening 24 is arranged above 13 the portions 25 of the arms 16 of the member 17 just to the rear of the projections 14. Opposite the opening 24 I bend the inner edge of the flange 5 downwardly forming a depending wall 26 and I provide this wall 20 26 with an opening 27 in alignment with the opening 24 to receive the point 28 of the key. The prongs or projections 23 are flat and parallel with each other and are adapted to be entered through the slot 24 extending 23 parallel with the top and bottom of the box and after being entered as best shown in Figure 10, the key can be rotated to cause the projections 23 to press the arms 16 downwardly as shown in dotted lines in Figure 30 8 and thus withdraw the projections 14 below or down to the top of the flange 5 and permit the free rotation of the cover.

The arms 16 are formed downwardly between the ends of the member 17 and the 35 projections 14 are formed up by bending lateral projections upwardly, shoulders 29 being provided on the projections to engage the flange 5 and prevent the arms 16 rising far enough to cover the openings 40 through which the key is entered.

My improved coin slot guard consists of two spring wire U-shaped members 30, one arranged above the slot 9 and the other below the slot although in some instances but 15 one of these members is necessary.

Where I use one of these wire guards, I provide a sheet metal cover 31 for the spring member 17, said cover having an extension 32 on one end, spaced from the 50 flange 5, and providing a flat pocket 33 for receiving one of the guards 30. The ends 34 of the guard 30 are bent downwardly and rearwardly to present inclined surfaces 35 to the slot 9 and I secure the U-shaped wire 55 guard 30 to the part 32 of the fixed guard 31 by striking up a tongue 36 out of the guard 31 and bending it downward over a U-shaped bend 37 at the middle portion of the guard 30, the plate 32 being provided with openings 60 38 through which the ends 34 are projected into the path of the coin as it enters the bank. As a coin is inserted into the bank through the slot 9, it forces the prongs 34 of the guard 30 out of its path, the U-shape of the 65 guard 30 permitting the end portions 39 to

rise away from the fixed guard or plate 32 for this action.

In addition to the guard 30 arranged as described, I sometimes arrange a duplicate guard 30 below the slot 9 providing a fixed 70 housing 40 for receiving and holding this duplicate guard. The housing 40 has openings 41 through which the ends 34 of the guard project into the path of the coin as it is entered through the slot 9. This housing 40 is adapted to be secured to the bottom of the box by tongues 42 which project through suitable openings in the inside member 43 of the bottom cover 3 of the box. 75

To prevent the key 21 being inserted too 80 far, I provide an upwardly extending flange 44 on the inner edge of the guard 31 having a part 45 extending over the opening 27 through which the point of the key projects, the end of the key being adapted to contact with the projection 45 and causes the projections 23 to be properly registered with the two arms 16 of the locking member 17. 85

To prevent the possible depressing of the 90 two arms 16 by some implement other than the key which is provided, I strike up a projection 46 out of the bottom wall of the guard 31 in position to enter the opening 27 between two projections 23 of the key. That is, this upstanding wall 46 projects 95 between the two parts 16 of the locking member 17 and is in alignment with the opening 24 through which the key is entered and prevents the simultaneous engagement of the two arms 16 except by a key of the form shown having a pair of projections 23, one for each of the arms 16, and provided with a slot or opening between the projections for passing the upstanding wall 46. 100

For securing the guard 31 to the flange 5 in addition to the bent over projection 20, I provide a similar struck up lug 47 at the opposite end of the member 31. As this member 31 has considerable length it might 110 spring downwardly between its ends and to prevent this distortion, I provide the portion 48 of the member 31, which guards the locking member 17, with a depending flange 49 at its outer edge of a length to cause its lower edge 50 to rest on the bottom plate 43 of the box. 115

It will now be understood that both the locking mechanism and the slot guard are 120 very substantial in that all of the parts are thoroughly guarded against pressure of the contents of the bank; that they are all simply constructed; and that they are not apt to be readily or easily distorted out of proper operating condition.

As many modifications of my invention will readily suggest themselves to one skilled in the art, I do not limit or confine my invention to the specific details of construction herein shown and described. 130

I claim:

1. In a coin bank, a casing comprising two parts adapted to be interlocked by relative rotation, means for locking the two parts against rotation to prevent their separation, comprising two projections arranged one radially within the other, on one member and normally extending beyond the joining plane of the two members, the other member having openings for receiving said projections when the two are in interlocking position, in combination with a rigid key having a projecting part for withdrawing each projection, a guard arranged between the two projections and a slot in the key for passing said guard as the key is rotated to withdraw the projections.

2. In a safe, a body and a cover arranged to be interlocked upon relative rotation, a pair of radially spaced projections carried by the body and arranged to extend beyond the meeting plane of the two parts, means yieldingly holding said projections in locking position, said projections adapted to be depressed by the cover as the cover is placed on the body, the cover provided with openings for receiving the projections as the cover is rotated to locking position, a fixed partition extending between the two projections, and a key having a slot to receive said partition and adapted to be rotated to withdraw both said projections, as and for the purpose specified.

3. In a coin bank of the kind described, a body having an open top, a removable cover for closing said top, the body provided with a slot through which coins can be inserted, a guard for the slot comprising

a U-shaped wire member mounted within a housing adjacent to the slot, the ends of the wire member projecting through openings in the housing into the path of entering coins, said ends being bent inwardly to present inclined surfaces to the coins as they are entered, as and for the purpose specified.

4. In a coin bank of the kind described, a body having an open top, a removable cover for closing said top, the body provided with a slot through which coins can be inserted, guard means for said slot comprising two U-shaped wire members, one mounted at each side of the slot, housings within which the wire members are mounted, the ends of the wire members projecting through openings in the housings into the path of entering coins, said ends of the guards bent inwardly to present inclined surfaces to the entering coins, as and for the purpose specified.

5. In a coin bank of the kind described, a body having an open top, a removable cover for closing said top, a spring member for locking the cover on the body, a coin slot in one side of the body, a housing within the body adjacent to said slot, said housing adapted to guard said spring member, a U-shaped wire member secured within said housing, its ends projecting through openings in the housing into the path of entering coins, said ends bent inwardly to present inclined surfaces to the coins, as and for the purpose specified.

Signed at Chicago, Illinois, this 27th day of April, 1922.

FRANK MADLE.
